INSECTICIDE COMPOSITION

William Moore, Chappaqua, N. Y., assignor to
American Cyanamid Company, New York,
N. Y., a corporation of Maine

No Drawing. Application August 15, 1931, Serial
No. 557,387

3 Claims. (Cl. 167—30)

This invention relates to insecticidal and fumigant compositions and is concerned more particularly with a solution in volatile organic solvents of a specific class of organic compounds.

5 I have discovered that valuable insecticidal properties are exhibited by the group of organic chemical compounds having most probably the following structural formula:

10

in which R represents an aryl group having the formula C_nH_{2n-7} . This group of chemical compounds includes a large number of substances of which the following are typical:

15 Diphenyl

Diphenyl methane

Dibenzyl (diphenyl ethane)

Diphenyl methyl ethane

20 Symmetrical or unsymmetrical diphenyl dimethyl ethane

Diphenyl propane, etc.

With the exception of diphenyl, these compounds which I have found suitable as insecticides may be represented by the following formula:

25 in which X and X' represent hydrogen or various alkyl groups, and n represents any whole number.

Typical insecticidal compositions are as follows:

Example 1

Parts by weight

Diphenyl	10
Solvent naphtha	90

Example 2

Parts by weight

Dibenzyl	10
Solvent naphtha	90

Example 3

Parts by weight

Diphenyl methane	10
Solvent naphtha	90

The compositions containing my insecticides are efficient for moths in their various forms, roaches, water bugs, ants and the like. My insecticides are particularly valuable since they have the property of penetrating to a marked degree. Thus, in one test, I put a number of moth larvae in cages and sewed the cages inside 10" x 10" mohair pillows stuffed with horse and pig hair. The pillows were then sprayed with the solutions described, and after one week the pillows were

opened and the moth larvae examined. In every case, it was found that a kill of over 90% was obtained, and in most cases the kill was 100%. In a series of check tests, without the insecticides, the kill ranged from 0 to about 15%.

5 The insecticides of my invention are definite moth-proofing agents but because of their volatility, the moth-proofing effect is of a more or less temporary nature. However, by mixing with my compositions moth-proofing agents of a more permanent nature such as, for instance, the cinchona alkaloids, a more permanent effect is obtained. Mixtures of this kind are especially valuable since the usual moth-proofing agents merely serve to protect the surface material and, as in the case with overstuffed furniture, infested with moths, the usual moth-proofing agent will protect the surface but the moths which are inside of the furniture will not ordinarily be killed and will continue to breed and attack such materials as may be available. By the use of my insecticidal compositions, however, the moths and their larvae, both inside as well as outside the furniture, will be killed, and any additional moth-proofing agent will act to keep the furniture 20 moth-free.

25 It will be apparent that my invention is susceptible of many changes and variations in the details set forth, without departing from the spirit and scope thereof. The proportions may be varied as desired, and in some cases, mixtures of the insecticides may be used. While it is not absolutely necessary, I prefer to utilize my insecticides in solution in the various known organic solvents and solvent mixtures since this gives exceptional ease of application and assists in penetration of the insecticide. Suitable other changes may be made as desired without departing from the spirit and scope of the invention except as defined in the appended claims.

30 I claim:

35 1. An insecticidal composition comprising a solution in an organic solvent of a compound having the following structural formula:

40 in which X and X' represent hydrogen or alkyl groups and n represents a whole number.

45 2. An insecticidal composition comprising a solution in an organic solvent of diphenyl ethane.

50 3. An insecticidal composition comprising a solution in an organic solvent of diphenyl methane.

WILLIAM MOORE.
